R. HOFFMAN.

MEANS FOR CONTROLLING AUTOMATIC WATER HEATERS.

APPLICATION FILED OCT. 6, 1913.

1,121,102.

Patented Dec. 15, 1914.

UNITED STATES PATENT OFFICE.

RUDOLPH HOFFMAN, OF CHICAGO, ILLINOIS.

MEANS FOR CONTROLLING AUTOMATIC WATER-HEATERS.

1,121,182.

Specification of Letters Patent. Patented Dec. 15, 1914.

Application filed October 6, 1913. Serial No. 793,562.

To all whom it may concern:

Be it known that I, RUDOLPH HOFFMAN, a citizen of the United States, residing at Chicago, in the county of Cook and State of Illinois, have invented certain new and useful improvements in Means for Controlling Automatic Water-Heaters, of which the following is a specification.

One of the objects of this invention is to provide means for positively shutting off the flow of gas to the burner, in case the means provided for normally closing or shutting off the flow of gas should fail to operate.

Another object of the invention is to regulate the supply of fuel in accordance with the rate at which hot water is being drawn.

The invention also relates to the other and further improvements in automatic water-heaters hereinafter set forth.

In the accompanying drawings Figure 1 is a vertical central sectional view through an apparatus embodying the features of my invention. Fig. 2 is a front elevation of the apparatus, with certain parts in section. Fig. 3 is a plan view of the piston. Fig. 4 is a view of the upper end of the piston rod and a sleeve on the piston.

The water container and the burner or heater may be of any well-known or suitable construction, and therefore are not illustrated herein, only the means for controlling the flow of fluid fuel to the burner or heater being shown. Said controlling means may be located and mounted in any suitable position and relation to the water container and the heater. The illustrative embodiment herein shown comprises a base 1 on which is mounted a U-tube 2, the branch 3 of which is connected to the fuel supply, and the branch 4 being in communication with the burner. Also mounted on the base 1 is a cylinder or well 5, the lower end of which communicates with the lower end of the U-tube 2 through a passage 6. Within the well or cylinder 5 is a piston or plunger 7. 8 indicates a suitable quantity of mercury or other liquid. When the plunger 7 is in its lower position, the mercury occupies the lower part of the U-tube 2 and prevents communication between the two branches 3 and 4 thereof, thus cutting off the flow of fuel to the burner. When the plunger 7 is raised, the mercury flows through the passage 6 into the lower end of the well 5, thereby leaving the U-tube 2 unobstructed to the flow of fuel.

Mounted on the base 1 above the well or cylinder 5 is a cylinder 9, the lower end of which is arranged to communicate with the water-container through a pipe 10. The cylinder 9 communicates with the house system or service pipes through a pipe 11 and a series of ports 12 or their equivalent. A piston rod 13 is guided for vertical movement in a stuffing box 14 on the lower head of the cylinder 9 and in a bracket 15. Upon the portion of the piston rod 13 which projects into the cylinder 9 is slidably mounted a piston 16 having a tubular stem 17 that fits slidably upon the rod 13. Suitable means may be provided for preventing rotation of the piston 16, as, for example, a stem 18 and a tubular guide 19. Below the piston 16 is a collar 20 fixed to the piston rod 13. In the piston and the collar are openings 16^a and 20^a, respectively, adapted to register under certain conditions, as will appear hereinafter. A coiled spring 21 interposed between the upper head of the cylinder 9 and the piston 16 tends to hold the latter against the collar 20.

Fixed in the end of the piston rod 13, above the upper end of the tubular stem 17, is a pin 22, adapted to overlie the upper end of said stem. When said pin overlies the upper end of the stem 17, the openings 16^a and 20^a are out of register; if an outlet in the house system is then opened, water flows from the heater through the pipe 10 into the cylinder 9, raising the piston 16 and flowing through one or more ports 12 into the pipe 11 and thence to the house system. When the piston 16 is thus lifted the piston rod 13 is likewise raised. The lower end of said rod is attached to the stem 23 of the plunger or piston 7 through the medium of a torsion spring strip 24; therefore, when the piston 16 is raised, as just described, the plunger 7 is raised to allow mercury to flow out of the U-tube 2, and thus open communication between the source of supply of fuel and the burner.

The greater the number of faucets opened in the house system, the higher the rise of the piston. Thus it will be seen that when but little hot water is being drawn, the plunger 7 will rise but little, and only a relatively small passage will be provided through the U-tube 2 for the fuel. When much water is being drawn, a proportionately large flow of fuel is permitted.

Means is provided for disconnecting the

piston 16 and the piston rod 13 when water of a predetermined temperature is flowing through the pipe 11. This means may include a thermostat of any suitable construction. Herein I have shown a thermostatic tube 25 exposed to the heat of the water flowing through the pipe 11. Within said tube is a rod 26 bearing against any common or suitable means 27 for multiplying the movement of the rod. Such movement-multiplying means is connected to a rod 28 which is guided for horizontal movement on the bracket 15. The rod 28 bears against an arm 29 pivoted on said bracket. At the other side of the arm 29 is a stud 30 which is fixed in the piston rod 13. The arm 29 is sufficiently broad so that the stud 30 does not pass above or below said arm in the reciprocating movement of the rod 13. A spring 31 tends to push the rod 28 against the arm 29.

In the tubular stem 17 is a vertical slot 32 adapted to receive the pin 22. At one side of the slot 32, the upper end of the stem 17 is cut away to form a slightly inclined surface 33 which is in a lower plane than the surface at the opposite side of the slot.

Two stop pins 34 are fixed to the upper end of the cylinder or well 5. Attached to the stem 23 is a pin 35 which is arranged to lie against the stop pins 34 and thus serve as an abutment for the torsion spring strip 24.

When the temperature of the water flowing through the pipe 11 rises to the predetermined point, the expansion of the thermostatic tube 25 permits the spring 31 to press the arm 29 against the stud 30, thereby turning the piston rod 13 against the influence of the torsion spring 24 until the pin 22 is in register with the slot 32. The plunger 7 will thereby be disconnected from the piston 16, and will drop and shut off the flow of fuel to the burner. If the rate of discharge from the house system is sufficiently great, the piston 16 will remain up. If the flow is comparatively small, so that the ports 16^a and 20^a will suffice therefor, the piston will descend under the action of the spring 21. When the tube 25 cools by reason of the flow of cool water past it, the torsion spring 24 will turn the pin 22 out of register with the slot 32, thereby carrying the ports 20^a out of register with the ports 16^a, whereupon the pressure of the flowing water will raise the piston and the plunger 7, thus opening the gas valve. As soon as the water reaches the desired degree of warmth, the spring 31 will disconnect the plunger 7 from the piston, and thus cause the supply of fuel to be cut off. When the house outlets are closed, the piston 16 will descend; and when the water standing about the tube 25 has cooled sufficiently, the spring 24 will turn the rod 13 until the pin 22 is on the inclined surface 33, said surface act-

ing to draw the collar 20 tightly against the piston.

It will be apparent that if the plunger 7 should fail to descend, fuel would continue to be supplied to the heater, notwithstanding the fact that no water was being drawn. To obviate this possibility, I have provided the means to be now described.

A suitable number of hollow, expandable disks 36 are connected in series and supported above the cylinder 9. Each of said disks consist of two flexible diaphragms connected together at their peripheries. The series of disks 36 is connected to a tubular rod 37 which extends through a stuffing box 38 and into the cylinder 9. The lower end of the rod 37 is adapted to press against the upper end of the piston rod 13 and the upper end of the tubular stem 17. If desired, a collar or flange 39 may be provided on the lower end of the rod 37. Above said flange one or more openings 40 may be formed through the rod 37. 41 are fixed vertical guide rods. Mounted on the upper ends of these rods is an abutment 42 for the upper end of the series of disks 36, the position of the abutment on the rods 41 being adjustable by means of nuts 43. Slidably mounted on the rods 41 is a yoke 44 which passes around the lower end of the series of disks 36. Compression springs 45 hold the yoke against the lowermost disk and tend to contract the disks. The tension of the springs 45 may be adjusted by means of the nuts 46.

When the outlets of the house system are closed, the pressures at opposite sides of the piston are equalized by reason of inevitable leakage past the periphery of the piston. The water pressure within the hollow disks 36 overcomes the springs 45 and causes said disks to expand, thereby forcing the tubular rod 37 against the piston rod 13 and the stem 17. The water pressure is thereby utilized to force the plunger 7 into position to shut off the flow of fuel, in case the weight of said plunger and the force of the spring 21 have been insufficient to seat the plunger.

I would have it understood that the invention is not limited to the construction and arrangement of parts herein shown, as various changes may be made without departing from the invention as set forth in the appended claims.

I claim as my invention:

1. In an automatic water heater, a fuel valve comprising a U-tube, a well extending below the U-tube, a quantity of a heavy liquid in said well, a piston in said well for displacing said liquid from the well into the U-tube, said liquid receding from the U-tube sufficiently to allow fuel to flow through the U-tube when the piston is raised, a hot-water discharge pipe, an element affected by the flow of water through said pipe, and an

operating connection between said element and said piston.

2. In an automatic water heater, a fuel valve comprising a U-tube; a well communicating with and extending below the U-tube; a quantity of a heavy liquid in said tube and well; and a piston in said well; a hot-water discharge pipe; an element affected by the flow of water through said pipe; and an operating connection between said element and said piston.

3. In an automatic water-heater, a fuel valve; a hot water discharge pipe; a cylinder communicating with said pipe; a hollow expansible element located outside of the cylinder and communicating with said cylinder and adapted to be expanded by the pressure of the water in said element and cylinder; connections between the valve and said element for closing the valve; and a piston in said cylinder arranged to act upon said connections, for opening the fuel valve.

4. In an automatic water heater, a fuel valve; a hot-water discharge pipe; a hollow expansible element; a tubular rod establishing communication between said hollow element and said pipe, said element being adapted to be expanded by the pressure of the water in said element and pipe; and a member attached to said fuel valve, said tubular rod being arranged to press against said member when said element is expanded to close the valve.

5. In an automatic heater, a fuel valve; a hot-water discharge pipe; a cylinder in said pipe; a piston in said cylinder arranged to be moved by the flow of water through said cylinder; a tubular stem attached to said piston; a piston rod slidable in said stem and connected to said fuel valve; a pin fixed to said piston rod, said tubular stem having a longitudinal slot for the reception of said pin; and means affected by the temperature of the water flowing through said pipe for turning said piston rod to place the pin in alinement with the slot, means being provided which tends to turn the piston rod to place the pin out of alinement with the slot.

6. In an automatic heater, a fuel valve tending to close; a hot-water discharge pipe; a cylinder in said pipe; a piston in said cylinder arranged to be moved by the flow of water through said cylinder; a tubular stem attached to said piston; a piston rod slidable in said stem and connected to said fuel valve; a pin fixed to said piston rod, said tubular stem having a longitudinal slot for the reception of said pin; and means affected by the temperature of the water flowing through said pipe for turning said piston rod to place the pin in alinement with the slot, and thus permit the fuel valve to close.

7. In an automatic heater, a fuel valve;

a hot-water discharge pipe; a cylinder in said pipe; a piston in said cylinder arranged to be moved by the flow of water through said cylinder; a tubular stem attached to said piston; a piston rod slidable in said stem and connected to said fuel valve; a pin fixed to said piston rod, said tubular stem having a longitudinal slot for the reception of said pin; means affected by the temperature of the water flowing through said pipe for turning said piston rod to place the pin in alinement with the slot; a hollow expansible element in communication with the cylinder; and means operated by expansion of said element for closing said valve.

8. In an automatic heater, a fuel valve, a hot-water discharge pipe, a cylinder in said pipe, a piston in said cylinder arranged to be moved by the flow of water through said cylinder, a piston rod for said piston, said rod being connected to the fuel valve, a collar on said piston rod at the inlet side of the piston, said collar and piston having ports adapted to register, and means controlled by the temperature of the water flowing through said pipe for causing relative turning movement between the piston and the collar to carry said ports out of register with each other.

9. In an automatic heater, a fuel valve, a hot-water discharge pipe, a cylinder in said pipe, a piston in said cylinder arranged to be moved by the flow of water through said cylinder, a tubular stem attached to said piston, a piston rod connected to said fuel valve, a pin fixed to said piston rod, said tubular stem having a longitudinal slot for the reception of said pin, means affected by the temperature of the water flowing through said pipe for turning said piston rod to place the pin in alinement with the slot, a collar on the piston rod at the inlet side of the piston, said piston and collar having ports which register when the pin is in alinement with the slot, and means tending to turn the piston rod to place the pin out of alinement with the slot and carry the ports in the collar out of register with the ports in the piston.

10. In an automatic heater, a fuel valve, a hot-water discharge pipe, a cylinder in said pipe, a piston in said cylinder arranged to be moved by the flow of water through said cylinder, a piston rod movable by the piston and connected to said valve, a hollow expansible element having a tubular rod communicating with the interior of said element and also communicating with said cylinder, said tubular rod being alined with and arranged to press against said piston rod to close the fuel valve.

11. In an automatic heater, a fuel valve, a hot-water discharge pipe, a cylinder in said pipe, a piston in said cylinder arranged

to be moved by the flow of water through said cylinder, a piston rod movable by said piston and connected to said valve, a hollow expansible element located outside of the cylinder, said element having a tubular rod communicating with the interior of said hollow element and extending through one end of the cylinder, said tubular rod being alined with and arranged to press against 10 said piston rod to close the fuel valve.

12. In an automatic heater, a fuel valve, a hot-water discharge pipe, a cylinder in said pipe, a piston in said cylinder arranged to be moved by the flow of water through 15 said cylinder, a connection between the piston and the valve for operating the latter, a spring tending to move the piston in the direction to close the valve, and supplementary means responsive to the pressure of the 20 water in the cylinder and also arranged to

move the piston in the direction to close the valve.

13. In an automatic heater, a fuel valve, a hot-water discharge pipe, a cylinder in said pipe, a piston in said cylinder arranged 25 to be moved by the flow of water through said cylinder, a piston rod for the piston, a connection between the piston rod and the valve for operating the latter, means tending to move the piston in the direction to 30 close the valve, and supplementary means responsive to the pressure of the water in the cylinder and arranged to move the piston rod in the direction to close the valve.

In testimony whereof I affix my signature 35 in the presence of two witnesses.

RUDOLPH HOFFMAN.
